BYRD C. ROCKWELL, OF CAMDEN, ARKANSAS.

WOODEN BUILDING CONSTRUCTION.

1,265,250.

Specification of Letters Patent. Patented May 7, 1918.

Application filed August 29, 1917. Serial No. 188,856.

To all whom it may concern:

Be it known that I, BYRD C. ROCKWELL, a citizen of the United States, residing at the city of Camden, county of Ouachita, and 5 State of Arkansas, have invented a certain new and useful Improvement in Wooden Building Construction, of which the following is a full, clear, and exact description, such as will enable others skilled in the art 10 to which it appertains to make and use the same, reference being had to the accompanying drawings, forming part of this specification.

This invention relates broadly to wooden 15 building structures, and pertains specifically to an improved construction for architectural pieces suitable for use in interior finish and fittings, such as casings, wainscoting, paneling, doors, and the like.

20 In material used for interior finishing, doors, and the like, it is desirable to have the pieces clear and sound and of good grain marking so as to afford a handsome finish and assure durable joining. In many places, 25 pieces of considerable thickness are required, for example, in door stiles, ceiling beams, casing soffits, and the like. In many woods, clear pieces of sufficient thickness are very rare and are very costly. In other woods, 30 it is practically impossible to dry pieces of sufficient thickness without their checking. Some woods, which are of proper texture, are cut into veneer, which is then glued to a cheaper wood to form the finish surface. 35 Many woods, however, due to certain inherent characteristics, cannot be cut into veneer.

The object of my invention is to provide a 40 construction whereby thin sawed pieces suitable for a finish surface may be suitably joined to provide members of the proper dimensions. Ancillary objects of the invention include the provision of such a construction which may be manufactured very economically, so as to produce a very great saving 45 over solid or finished material; to provide a construction wherein the parts are firmly secured in place in such fashion as to positively prevent any warping, distortion or checking of the member or of the finish 50 pieces; to provide a construction which is susceptible of use to produce pieces of any desired dimensions; and to provide a construction which permits of the cutting necessary in joining.

55 Other objects will be obvious or pointed

out hereinafter, reference being had to the accompanying drawings, in which—

Figure 1 represents a perspective view of a piece embodying my improved construction;

Fig. 2 is a detail representing a longitudinal section through such a piece at one of the tenon locks;

Fig. 3 is a detail representing a transverse section;

Fig. 4 is a detail illustrating the manner of construction, the same being in the nature of a side elevation of a piece with parts broken away.

Referring to these illustrations in detail 70 by use of the reference numerals, let it be understood that the numerals 1 and 1' designate face or finish pieces. These are preferably thin sawed parts having the grain running longitudinally, and of proper grade 75 and graining to afford the desired finish face or surface. They have the width and length desired for the finished member, but their thickness represents only a fraction of the total thickness of the complete member. 80 Due to this fact, their cost represents only a fraction of the cost of a solid piece of suitable grade having the total thickness of the completed member. It having been determined which of the faces of these pieces shall be 85 the finish faces, each piece is grooved transversely on the side opposite the finish face to form shallow keyways designated by the numeral 2. The margins of these keyways are undercut to form the locking shoulders 90 designated by the numeral 4. The shoulders 4 at the opposite sides of a groove preferably extend parallel to each other transversely of the piece. These grooves are formed in the pieces 1 and 1' at any desired longitudinal 95 intervals, their spacing being the same in the two pieces. Tenon pieces 5, in the nature of locking or wedging members, are provided, their thickness being such that when taken with the thickness of the pieces 1 and 1' they will equal the desired thickness of the completed member. These tenon members may be made of any material having the desired firmness, and when made of wood, as is preferable, they should be formed 100 with the grain running longitudinally. On opposite sides the tenon members are formed with the extending dove-tailed tenons 6 adapted to seat within the grooves 2 with their marginal portions behind the shoulders 105 110

4. The length of the dove-tailed tenons on a member 5 is less than the width of a slot 2, so that the tenons on two of the members 5 may be accommodated within the same slot. 5 As will be best seen in Fig. 4, in which the angle is somewhat exaggerated, the edges 5^a of the two associated members 5 are arranged to bear upon each other, and are cut on a slight angle or miter. The total length of 10 the tenons 6 of the two associated tenon members, measured at the wide side of one and the narrow side of the other, is somewhat greater than the total width of the groove 2 in which they are to seat. The 15 amount of this excess width may vary according to the compactness of the various woods.

In forming the member of the pieces 1 and 1', and tenon members 5, the said pieces 20 are placed on edge in a form which will hold them against movement apart, the grooves 2 in one piece being disposed opposite corresponding grooves in the other piece. Streaks of glue are applied along 25 the margins of the grooves and the shoulders 4, across the pieces, and also along lines which mark the extent of the tenon members 5 from the grooves. One of the tenon members 5 is then placed between the members 30 1 and 1', the wide side of its tenons 6 being introduced first, and is forced home between the members 1 and 1' with the margins of its tenons behind the shoulders 4 of the two pieces. The associated tenon 35 member 5 is then placed in position between the members 1 and 1' with the margins of its tenons behind the other shoulders 4 of the grooves, and with its edge 5^a against the similar edge of the associated tenon 40 member. The shorter edge of this second member 5 is introduced first, as will be clearly understood by reference to Fig. 4, 45 and suitable pressure is then applied to the member 5 to force it home between the members 1 and 1'. As it moves inwardly, due to the angle or miter of the co-operating edges 5^a, the tenon members 5 will be moved oppositely longitudinally of the members 1 and 1', and will exercise a wedging action 50 upon the latter by virtue of the engagement of the tenon members 6 against the shoulders 4. The drying of the glue will secure the members in this relationship, in which the members 1 and 1' are firmly locked together by virtue of the dove-tailed engagement of the tenons 6 in the grooves 2.

It is essential that the co-operating faces 5^a of the associated tenon members be absolutely square with their side faces, as it is 60 their bearing upon each other which holds the members 1 and 1' in alinement. The intervals between the tenon locks thus formed may be left unfilled, or may be filled with any desired suitable material. The 65 edges of the member may be suitably faced

with a thin strip 7 of suitable finished material, or if intended to receive paneling, or to be joined with other members, may be finished with any desired beading 8.

By virtue of this construction, I effect a great saving over both present forms, *i. e.*, by use of the thin finish pieces the completed member may be produced at a cost much below the cost of a suitable solid piece of the same dimensions, while the cost of material and of production in my construction is far below the cost of producing a suitable member of the same dimensions by the use of veneer to supply the finish surface, as it requires less material, smaller pieces, 75 and only a very small fraction of the amount of glue. Moreover, a very decided saving is effected in the amount of labor required.

It is obvious that members may be made up in this fashion to supply a wide variety 80 of requirements, as to dimension, form and finish, and that they are susceptible of use in any place where finish material is required. The tenon locks may be disposed at any desired point to accommodate the joints with 85 associated members, hinges, locks, and other fixtures. The structure is especially useful, moreover, in various forms of furniture, as it affords a very light construction, while at 90 the same time one very rigid and strong and 95 free from distortion.

While the form herein illustrated and described is illustrative of my invention, I am aware that it is not the only form in which the invention may be embodied or practised, and hence it is my purpose and intent that the appended claims comprehend not only the form shown, but also any and all modifications, adaptations, and general arrangements wherein the substance and 100 essential spirit of the invention is embodied or employed.

What I claim is:

1. A wooden building construction formed of two boards having longitudinal grain, said 110 boards being disposed with side surfaces facing and being provided with grooves extending transversely in said facing sides, the said grooves being undercut into the material at their margins to provide overhanging 115 shoulders, a tenon member having tenons on opposite sides arranged to register in said grooves and fit behind the shoulder at one end of a groove on each board, and a co-operating tenon member having tenons 120 adapted likewise to fit within said grooves and behind a shoulder at the opposite end of each groove, said tenon members bearing on each other along margins extending obliquely relative to the margins of the 125 grooves.

2. A wooden building construction formed of two boards each having a dove-tail groove extending transversely at one side thereof, said boards being disposed with the grooves 130

counterfacing, and a pair of coöperating wedge members disposed between the boards and each having dove-tailed tenons on opposite sides, one tenon of each wedge member fitting within the dove-tail groove of one of the boards and the other tenon of each wedge member fitting within the dove-tail groove of the other board, said wedge members having bearing upon each other within the said grooves on margins extending transversely of the boards, the summational length of the tenons seating in a groove exceeding the length of the groove when the material in which they are formed is at its normal compression or density.

3. A wooden building construction comprising a pair of boards each formed with a transverse groove on one face thereof, said boards being disposed with the grooves counterfacing, and a pair of coöperating wedge members disposed between the boards, said wedge members each having laterally extending tenon portions seating within the grooves of the two boards, said wedge members having bearing upon each other on margins extending obliquely to the margins of said grooves, the summational length of said tenon portions seating in a groove exceeding the length of the groove when the material in which they are formed is at its normal compression or density.

4. A built-up wooden structural member formed of two boards each provided with a plurality of transverse grooves in one face, the said boards being arranged spaced apart from each other and with their grooved por-

tions counterfacing, and tenon members disposed between the boards and retaining them in fixed relationship; there being a plurality of said tenon members disposed in coöperation with each of the grooves in each of the boards, and each of said tenon members being formed with a laterally extending tenon engaging in a portion of one of the grooves in each of the boards, the tenon members seating in a groove having bearing upon each other on margins extending obliquely relative to a margin of said groove, and the summational length of the tenon seating in a groove exceeding the length of the groove when the material in which the tenons or the grooves are formed is at its normal compression or density.

5. The method of forming a wooden structural member which consists in forming boards with transversely extending dove-tail grooves in one side of each, disposing said boards with said grooves in counterfacing relationship, and forcing into said grooves by movement transversely of said boards wedging tenon members having tenons seating in said grooves and coöperating with the margins thereof, the relative movement of said tenon members operating to increase the distance between the effective margins of their tenons so as to exert a wedging pressure upon the margins of the grooves of both the boards.

In testimony whereof I hereunto affix my signature, this 22 day of August, 1917.

BYRD C. ROCKWELL.
